UNITED STATES PATENT OFFICE.

VICTOR DORNBURGER, OF SAN JOSE, CALIFORNIA.

INKWELL.

Application filed February 10, 1921. Serial No. 443,960.

To all whom it may concern:

Be it known that I, VICTOR DORNBURGER, a citizen of the United States, and resident of San Jose, in the county of Santa Clara and State of California, have invented certain new and useful Improvements in Ink-wells, of which the following is a specification.

My invention relates particularly to a type of ink well designed to be permanently arranged in a desk top.

It is the object of my invention to provide an ink well so constructed as to carry a large amount of ink, and one that can be conveniently arranged in a desk top and that will protect its contents at all times from evaporation or becoming befouled with foreign matter. A further object is to provide an ink well of the character indicated so constructed and positioned as to obviate all possibility of the ink overflowing on to the desk and that will provide a neat, durable and practical device of particular adaptability for use in school room equipment.

In the drawing:

Figure 1 is a plan view of the device in position at the side of a school desk.

Figure 2 is a side elevation of the same, part broken away.

Figure 3 is a perspective view of the supporting case.

Figure 4 is a perspective view of the ink receptacle.

Figure 5 is a section on line 5—5 of Figure 1.

Referring more particularly to the drawing, 1 indicates a portion of the top of a school desk and 2 the side portion of the desk over which the top 1 overhangs. At 3 is shown a sheet metal case of exactly the same width as the overhanging portion of the top 1, the inner side 4 of the case engaging the outer side of the side portion 2 of the desk, and the outer side 5 of the case extending upwardly and being set into the edge of the desk top as shown. The ends 6 of the case 3 are formed to engage the bottom surface of top 1 and are provided with slots 7 to engage screws 7^a set in said top so that by loosening the screws 7^a the whole case 3 may be slipped free of the desk top.

Fitting snugly in case 3 is a glass ink receptacle as 9, in the present case entirely enclosed except at the forward end of its upper side where an opening 10 is provided and which is also provided with a groove 11.

This forward portion of the receptacle is separated from the rear and main portion by a depending element 12 approaching but not contacting with the bottom of the receptacle. This element 12 prevents foreign matter such as paper, etc., from working back into the body of the well.

At 13 I show a plate set in flush with the upper surface of the desk and in alignment with case 3 and receptacle 9 and overlapping the forward portions thereof as shown in Figure 2. Plate 13 is provided with an opening 14 having substantially the same width at 15 as the portion 10 of the ink receptacle 70 and communicating therewith, and a narrower portion 16.

At 17 is shown a cover plate mounted in portion 15 of opening 14 and flush with the top of said plate and provided with depending lugs 18 pivotally mounted on a shaft 19 set in plate 13 as shown. The lugs 18 are formed with forwardly and upwardly curved bottom edges as shown at 20 and extend down into the groove 11 in interlocking relation thereto.

At 21 is a lever plate set flush with the upper surface of plate 13 and in portion 16 of opening 14 and extending into portion 15 of said opening as shown. Lever 21 is 85 provided with depending lugs 22 pivotally mounted on shaft 23 set in plate 13 and carries a pair of fingers 24 extending under and engaging the curved edges of lugs 18.

In its preferred practical application the structure is mounted in the edge of a desk as above set forth, where it occupies space ordinarily not used at all. This arrangement renders all of the balance of the desk, including the upper portion now largely 90 rendered useless by the ordinary ink well, available for other purposes. Placing the ink well at the side also renders it more convenient for use and permits the use of a large reservoir, the said reservoir being 100 freely available for filling and cleaning and sufficiently large to hold sufficient ink to last for a long period of time, and yet in no way interfering with the free use of both the interior and exterior of the desk.

By eliminating the necessity of the frequent filling of easily removable ink wells, the dangers attending such filling are reduced to a minimum or entirely eliminated. By means of the structure set forth the well 110 is entirely removed from the desk for filling, and need be filled but once in the

whole school year, and this operation in no way placing the material on the desk in jeopardy.

When in use a light pressure on the end 5 of lever 21 by the fingers of the hand holding the pen causes the fingers 24 on the said lever to operate on edges 20 of lugs 18 thereby throwing cover plate 17 upwardly into the position shown in Figures 10 2 and 3 whereupon a pen as 25 may be dipped into the reservoir 10 of the ink receptacle. Upon removing the hand from the lever 21 the said lever 21 and plate 17 15 automatically drop back to a closed position due to the location of their pivotal points. This automatically closing construction prevents evaporation of the ink and protects it from dust, etc., and yet permits it to be freely used without effort or 20 difficulty on the part of the user.

While I have herein shown and described one particular embodiment of my invention, it is to be understood that changes in form, construction and method of operation 25 may be made within the scope of the appended claims.

I claim:

1. An ink well for desks, comprising a receptacle, a top plate having an opening 30 through which access is gained to the ink receptacle, a sectional cover for the receptacle, the sections of which are pivoted independently in the opening of the top plate, and normally nesting cam fingers carried 35 by the cover sections whereby upon tilting one section to open the same the companion section will concurrently open.

2. A receptacle having an opening formed therein, a plate arranged thereover and provided with an opening communicating with 40 said first mentioned opening, a pin eccentrically arranged in the opening in said plate, a closure for said plate opening, de-

pending lugs on said closure revolvably engaging said pin and provided with outwardly extending and upwardly curving edges, a lever plate pivotally mounted in the same plane as said closure, and a pair of fingers formed on said lever plate and engaging the curved edges of the depending 50 lugs on said closure. 45

3. An ink well for desks, comprising a receptacle, a top plate having an opening through which access is gained to the ink receptacle, a sectional cover for the receptacle, the sections of which are pivoted independently in the opening of the top plate, 55 the meeting edges of the cover sections having respectively a wide tongue and recess fit whereby upon movement of the 60 tongue to open position a large opening to the receptacle will be provided, and means for effecting simultaneous movement to the cover sections.

4. An ink well for desks, a receptacle, 65 comprising a top plate having an opening through which access is gained to the ink receptacle, a sectional cover for the receptacle, the sections of which are pivoted independently in the opening of the top plate, 70 one cover section having a depressible wrist-supporting portion for raising the opposite end to open position, and a free cam connection between the cover sections for simultaneously raising the meeting edges of 75 the cover-sections.

5. An ink well for attachment to the ledge of a desk, comprising a case slidably removable from the ledge, an ink receptacle 80 removably contained within the case, said receptacle having a groove across its upper face, and a cover plate having a projection normally interlocking with the groove of the receptacle. 85

VICTOR DORNBURGER.
